UNITED STATES PATENT OFFICE.

SAM MORANO, OF WENDEL, WEST VIRGINIA.

RAIL ADJUSTING AND GAGING DEVICE.

1,290,288.

Specification of Letters Patent.

Patented Jan. 7, 1919.

Application filed September 18, 1918. Serial No. 254,587.

To all whom it may concern:

Be it known that I, SAM MORANO, a subject of the King of Italy, residing at Wendel, in the county of Taylor and State of 5 West Virginia, have invented certain new and useful Improvements in Rail Adjusting and Gaging Devices, of which the following is a specification.

This invention relates to certain new and 10 useful improvements in rail adjusting and gaging devices and has among its many objects the provision of a device of this character which is durable in construction, efficient in operation, and capable of being 15 easily placed into practical use.

Another object of the device is the provision of adjustable rail engaging members which slidably support a gaging device and are provided with means to move the same 20 toward and away from each other in order that rails may be accurately positioned parallel with each other at the proper distance apart.

A still further object of the invention is 25 the provision of a rail adjusting means with a normally operatively positioned gage thereon having depending pins or the like adapted to engage the inner faces of the balls of spaced rails when said rails are 30 positioned a proper distance from each other.

With the above general objects in view and others that will become apparent as 35 the nature of the invention is better understood, the same consists in the novel form, combination and arrangement of parts hereinafter more fully described, shown in the accompanying drawing and claimed.

In the accompanying drawing, in which 40 like reference characters indicate corresponding parts throughout the several views,

Figure 1 is a side elevational view of the present invention, with the rails positioned thereon as shown by dotted lines.

Fig. 2 is a plan view of the device shown in Fig. 1.

Fig. 3 is an enlarged detail view taken in longitudinal section through one end of the device and the adjacent rail, the movable rail holding member being indicated in an inoperative position by dotted lines.

Fig. 4 is a perspective view of the device shown in Fig. 3 with the rail and movable rail holding member removed, and

Fig. 5 is a perspective view of the movable rail holding member detached.

Referring more in detail to the several views, the present invention embodies a pair of aligned base members or plates 5 adapted to be supported upon the ground beneath 60 the rails 6 as shown in Figs. 1 and 3 by means of transverse supporting rods or feet 7, it being understood that the present device is, when in use, placed between the ties to which the rails 6 are secured. 65

The base plates 5 have the outer opposite ends thereof cut away as at 8 to provide pairs of legs 9 and 10 which are provided at their outer ends with inwardly extending integral rail base receiving jaws 11 and 12 70 respectively. The legs 9 and 10 are rigidly connected by one of the feet members 7 so as to strengthen the device.

Suitable brackets 13 are rigidly fastened 75 against the under faces of the legs 9 and 10 and said brackets support transverse pivot pins 14 on which are pivotally mounted the swinging rail holding members 15, said rail holding members 15 being of sufficient width to extend across the space between the legs 80 9 and 10.

The rail holding members 15 are each provided at its lower end with a horizontal portion 16 provided with a transverse aperture 17 through which the pivot pin 14 extends and the upper end of said rail holding member is provided with a rail base 85 engaging jaw 18.

Upon the upper faces of the legs 9 and 10 inwardly of the brackets 13 are rigidly 90 fastened aligned channel brackets 19 whose channels overlie grooves 20 in the adjacent portions of the upper faces of said legs. When the rail holding members 15 are positioned as shown in Figs. 1 and 2, a transverse key 21 is slidably positioned into the adjacent aligned brackets 19 and grooves 20 so as to bear against the inner faces of the rail holding members 15 and securely retain the latter with the jaws 18 firmly clamping 100 the bases of the rails 6. Any suitable means such as cotter pins 22 may be utilized to retain the keys 21 against displacement.

Rigidly fastened to the inner adjacent ends of the plates 5 are upwardly extending 105 upright posts 23 which are suitably braced by triangular brace members 24. These upright posts 23 are connected by means of a screw 25 so as to adjust the same and consequently the base members 5 to positions toward and away from each other as required. The screw 25 is threaded through one of the

posts 23 and is securely maintained against movement through the other post by means of collars 26, said screw being prevented from accidental withdrawal from the first-
5 named post by means of a nut 27 threaded upon the reduced end 28 of said screw. Any suitable means such as a removable handle 29 may be utilized to rotate the screw 25 and it will be obvious that when the screw is ro-
10 tated, the base members or plates 5 are moved toward or away from each other accord-
15 ing to the direction of rotation of the screw to thereby adjust the rails 6 accord-
20 ingly to a proper distance apart determined by the pins 30 which depend from the gage bar 31. The gage bar 31 is supported on the posts 23 in a horizontal position by means of suitable brackets 32, it being noted that said bar 31 is capable of sliding movement
25 through the brackets 32 relative to the posts 23.

In the operation of the present devices, the same is positioned as shown in Fig. 1 with the rails securely clamped in position
25 by means of the holding members 15 and the screw 25 is then rotated to move the base members 5 toward each other until the ball of the rail 6 at the left-hand side of Fig. 1 strikes the adjacent pin 30.

30 Further rotation of the screw 25 causes the rod 31 to be slid longitudinally until the adjacent pin 30 strikes the inner face of the ball of the rail at the right hand side of Fig. 1 and when this occurs the rails 6 are positioned at the proper distance apart.

From the foregoing description it is believed that the construction and operation of the present device will be readily apparent to those skilled in the art and while the
40 form of the invention herein shown and described is what is believed to be the preferable embodiment thereof, it is nevertheless to be understood that minor changes may be made in the form, arrangement, and com-

bination of parts without departing from 45 the spirit and scope of the invention as claimed.

What I claim as new is:—

1. A combined rail adjusting and gaging device including a pair of base members hav-
50 ing rail base clamping means upon the outer opposite ends thereof, upright posts rigidly carried by the inner adjacent ends of said base members, means connecting the said upright posts to cause movement of the same, 55 toward and away from each other, a horizontal gage bar slidably carried by said upright posts, and depending pins carried by said gage bar adapted for contact with the inner faces of the balls of said rails when
60 the rails are properly positioned.

2. A rail adjusting and gaging device comprising a pair of base members having rail clamping means upon the outer opposite ends thereof, means to adjust said base mem-
65 bers toward and away from each other, and a rail gage including a gage bar slidably supported by said base members for horizontal longitudinal movement, said gage bar being provided with depending rail contact-
70 ing means upon the free ends thereof.

3. A rail adjusting and gaging device in-
cluding a pair of aligned base plates having rail base clamping means upon the outer op-
75 posite ends thereof, upright braced posts ex-
tending upwardly from the inner adjacent ends of said base members, a screw swiveled in one of said posts and threaded through the other thereof, to cause movement of said base members toward and away from each
80 other, brackets secured to adjacent side edges of said upright posts above the base mem-
bers, a horizontal gage bar supported by said brackets for longitudinal sliding movement, and depending rail contacting pins carried
85 by the opposite ends of said gage bar.

In testimony whereof I affix my signature.
SAM MORANO.
